UNITED STATES PATENT OFFICE

2,524,302

SCAFFOLD

Jesse Mack Benson, Concord, Tenn., assignor to
Sasgen Derrick Co., Chicago, Ill., a corporation
of Illinois

Application July 8, 1946, Serial No. 681,965

1 Claim. (Cl. 304—16)

1

This invention relates to scaffolds and more particularly to scaffolds having improved scaffold brackets.

An object of this invention is to provide an improved scaffold and scaffold brackets for use with the improved scaffold winch in my Patent No. 2,424,910.

Another object of this invention is to provide an improved bracket for scaffolds having hook eyes on the upper ends of the arms in which the winch may be attached and a loop on one side for supporting a guard rail.

Still another object of this invention is to provide an improved scaffold bracket which is light weight and compact in construction and in which the supporting side arms may be folded into the base of the bracket to provide for a compact package which may be readily transported with a minimum of space.

With the above and other objects in view, my invention consists in the arrangement, combination and details of construction disclosed in the drawings and specifications, and then more particularly pointed out in the appended claim.

In the drawings,

Figure 1 is a front elevation, partly broken away, of a scaffold constructed according to an embodiment of my invention.

Figure 2 is a vertical section, partly broken away, taken on the line 2—2 of Figure 1.

Figure 3 is a horizontal section taken on the line 3—3 of Figure 2.

Figure 4 is a vertical section through the bracket in the folded position.

Figure 5 is an enlarged detail plan view, partly broken away, of the end of the bracket in Figure 4.

Figure 6 is a vertical section, partly broken away, taken on the line 6—6 of Figure 2.

Referring to the drawings, the numeral 10 designates generally a scaffold constructed according to an embodiment of this invention. The scaffold 10 comprises floor planks 11 supported between a pair of brackets 12 and a guard rail 14 supported above the planks 11 on the brackets 12.

The brackets 12 are formed of a pair of oppositely disposed inverted L-shaped strips of metal angle 15 spaced apart by a short cylindrical or tubular spacer 16. The angle members 15 are disposed in face abutting relation with one side 17 of each member extending outwardly at the upper end to provide a flat base on which the planks 11 may be supported. Bolts 18 along the length of the members 15 extend through the vertical arms 19

thereof and through the spacers 16 and are fixed in position by nuts 20.

On the rear or outer end of the brackets 12 there is provided a supporting rod 21 pivotally connected at their lower end between the angles 15. The rod 21 is substantially longer than one half the length of the angles 15 and is formed at its lower end with a loop 22 which is adapted to be closed loosely about the end spacer 16, whereby the rod 21 may pivot about the spacer 16 and in its folded position is adapted to lie between the angles 15. The upper end of the rod 21 is formed with a loop 24 in which a hook 25 beneath a winch 26 may be engaged in the raised or extended position of the rod 21. A rectangular U-shaped loop 27 is fixed on the outer side of the rod 21 near the upper end thereof and is adapted to support a guard rail 14. A small loop 28 is fixed on the rod 21 intermediate the length thereof for supporting an auxiliary guard cable when desired.

A shorter supporting rod 29 is pivotally connected to the front or inner end of the angles 15 and is formed with a loop 30 on its lower end for engaging loosely about the front spacer 16. The rod 29 is formed at its upper end with a loop 31 in which the hook 25 depending from a winch 26 may be engaged. The rod 29 is substantially shorter than one half the length of the angles 15 so that the rods 21 and 29 may be enclosed between the angles 15 in their folded position.

On each end of the bracket 12 there is fixed an angle 32 having a vertical side closing the space between the angles 15 which angles 32 provide a stop for the rods 21 and 29 in their extended position to prevent the rods 21 and 29 from being pivoted beyond a vertical position as shown in Figure 2.

For transporting this scaffold support 12 from place to place, the rods 21 and 29 are folded inwardly to be enclosed within the space between the angles 15 with only the loops 27 and 28 extending above the outline of the angles 15, thus providing a very compact and readily handled package, as shown in Figure 4.

In use as a scaffold the arms 21 and 29 are raised to a vertical position and a pair of brackets 12 may be spaced at any suitable distance apart below the planks 11, thereby being adaptable to various lengths of scaffold planks 11. Hooks 25 secured to winches 26 which are described in my copending application may be engaged in the upper loops 24 and 31 in the rods 21 and 29 respectively, for raising and lowering the scaffold

10 by an operator on the scaffold. A guard rail 14 may be installed in the loops 27 and when desired a cable or rope may be engaged in the loops 28 as an auxiliary guard cable.

I do not mean to confine myself to the exact details of construction herein disclosed, but claim all variations falling within the purview of the appended claim.

What I claim is:

A scaffold supporting bracket comprising a pair 10 of elongated oppositely disposed parallel extending angle members on which planks may be supported, means securing said angle members together in spaced apart relation longitudinally thereof, a first supporting rod having a loop formed on one end loosely extending between said angle members at one end of the latter, pivot means carried by said angle members extending through said loop for rockably connecting said rod to said angle members, a second supporting rod having a loop formed on one end extending loosely between said angle members at the other end thereof, pivot means extending through the loop of said second supporting rod for rockably

5 connecting said second rod to said angle members, and bent tabs formed on the opposite ends of said angle members closing the space between the latter and engageable with the adjacent ones of said supporting rods for limiting the rocking of said rods away from said angle members.

JESSE MACK BENSON.
